UNITED STATES PATENT OFFICE.

HOWARD T. CLODFELTER, OF BRUNO, MINNESOTA.

DESIGN FOR A TOILET-POWDER AND JEWELRY CONTAINER.

54,833.

Specification for Design.

Patented Apr. 13, 1920.

Application filed December 31, 1918. Serial No. 269,157. Term of patent 14 years.

To all whom it may concern:

Be it known that I, HOWARD T. CLODFELTER, a citizen of the United States, residing at Bruno, in the county of Pine and State of Minnesota, have invented a new, original, and ornamental Design for a Toilet-Powder and Jewelry Container, of which the following is a specification, reference being had to the accompanying drawing, forming part thereof:

Figure 1 is a side elevation of a toilet powder and jewelry container embodying my design,

Fig. 2 is a top plan view thereof, and
Fig. 3 is an end view.

I claim:

The ornamental design for a toilet powder and jewelry container, as shown.

HOWARD T. CLODFELTER.
